[57] CLAIM

The ornamental design for a combined pool and sandbox, as shown.

DESCRIPTION

FIG. 1 is a perspective view of a combined pool and sandbox showing my new design in the open position thereof;

FIG. 2 is a top plan view of the combined pool and sandbox of FIG. 1;

FIG. 3 is a side elevational view of the combined pool and sandbox of FIG. 2;

FIG. 4 is a bottom plan view of the combined pool and sandbox of FIG. 1;

FIG. 5 is an end elevational view of the combined pool and sandbox of FIG. 2 as viewed from right end thereof; and thereafter

FIG. 6 is a perspective view of the combined pool and sandbox illustrated in FIG. 1 in the closed position thereof.
